UNITED STATES PATENT OFFICE.

ARTHUR S. FUNK AND EDGAR S. BOTT, OF LA CROSSE, WISCONSIN, ASSIGNEES TO LA CROSSE RUBBER MILLS COMPANY, OF LA CROSSE, WISCONSIN.

DESIGN FOR A SHOE SOLE.

Application filed December 12, 1927. Serial No. 24,456. Term of patent 14 years.

To all whom it may concern:

Be it known that we, ARTHUR S. FUNK and EDGAR S. BOTT, citizens of the United States, residing at La Crosse, in the county of La Crosse and State of Wisconsin, have invented a new, original, and ornamental Design for Shoe Soles, of which the following is a specification, reference being had to the accompanying drawing, forming part thereof.

Fig. 1 is a face view of a shoe sole showing our new design. Fig. 2 is a longitudinal sectional view on line 2-2 of Fig. 1.

We claim:

The ornamental design for a shoe sole, as shown.

ARTHUR S. FUNK.
EDGAR S. BOTT.
